United States Patent Office

Des. 206,241

Patented Nov. 15, 1966

206,241

SHELF STANDARD

Martin Bard, 953 45th St., Brooklyn, N.Y.

Filed Sept. 9, 1965, Ser. No. 86,912

Term of patent 14 years

(Cl. D54—1)

Fig.1

Fig.2

FIG. 1 is an isometric view of a shelf standard embodying my novel design; and

FIG. 2 is a top view of the standard of FIG. 1.

The decorative shading seen in FIG. 1 appears on the exposed surface of both oblique sides of each standard.

The broken line showings are for illustrative purposes only.

I claim:

The ornamental design for a shelf standard, substantially as shown and described.
